UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

FUSE-PLUG.

1,350,111.

Specification of Letters Patent. Patented Aug. 17, 1920.

Application filed December 21, 1917. Serial No. 208,301.

To all whom it may concern:

Be it known that I, HENRY T. PAISTE, a citizen of the United States, residing in Philadelphia, Pennsylvania, have invented 5

5 Fuse-Plugs, of which the following is a specification.

This invention relates to a form of fuse plug having two separable parts of which one carries a fuse in such manner as to permit 10 of its convenient renewal, one object of said invention being to provide a compact, substantial and conveniently operable plug of the type noted.

It is further desired to provide a two-part 15 fuse plug of such construction that relative rotation of its parts is effectually prevented while at the same time good electrical contact between the fuse proper and certain conducting elements of the plug is assured.

20 Another object of the invention is to provide a novel form of fuse-carrying element for a two-part fuse plug, whose parts shall be so arranged and constructed as to permit of the rapid and convenient insertion of a 25 length of fuse wire in one of said parts.

It is also desired to provide a novel form of 30 fuse body including novel means for detachably engaging the screw or other holding member forming a part of the fuse-holding element with a view to mechanically connecting said body and element as well as insuring good electrical contact between a 35 length of fuse wire or strip and certain terminals respectively on the body and said element.

These objects and other advantageous ends I attain as hereinafter set forth, reference being had to the accompanying drawings, in which:

40 Figures 1 and 2, are respectively a side elevation and a plan of a fuse plug constructed according to my invention.

Fig. 3, is a vertical section on the line 3—3, Fig. 2,

45 Figs. 4 and 5 are perspective views of the fuse-carrying element of the plug, with the central terminal removed, and

Figs. 6 to 12 inclusive, are perspective views of various parts of the plug.

50 In the above drawings, 1 represents a fuse plug body preferably made of a vitreous material such as porcelain and consisting of a hollow cylindrical portion 2 having an outwardly extending flange 3 at one end. The 55 passage through the portion 2, while of any

section other than circular, is shown in the present instance as of hexagonal outline which within the flange 3 merges into a cavity of circular section, whose walls at two opposite points, are formed to provide rectangular recesses 4. The outer face of the flange 3 is provided with a series of radial grooves 5 and its lower edge adjacent the portion 2 is also formed with grooves 6.

The inner edge of said flange 3 is slightly 65 depressed, as indicated at 7, to provide a shoulder for the support of a circular mica plate 8, which is held in position to close the flanged end of the body by means of an inwardly flanged ring 9 of sheet metal which 70 extends down around the sides of the flange 3 and is turned inwardly as shown at 10 so that it is permanently held to the body 1. Said mica plate and retaining ring serve to 75 permanently retain in place a metal bridge piece 11 of channel section which extends diametrically across the opening through the flange 3 and has its ends fitted in the recesses 4 in the walls thereof. This bridge piece has a central threaded opening 12 for the reception 80 of a screw 13 hereafter referred to.

Mounted upon the cylindrical outer surface of the part 2 of the body is a threaded shell 14 of sheet metal having the general form of an Edison socket or lamp terminal 85 and made with its inner edge 15 turned in so as to project into an angular groove 16 formed in the part 2 of the body adjacent the flange 3, while the opposite end of said part is spun or otherwise turned over the 90 end of said part 2 as indicated at 17, having through it a hexagonal or other opening of the same outline as that of the passage through the fuse body.

The second member of the fuse plug consists in the present instance of a hexagonal prismatic piece 18 having at one end an outwardly extending flange 19 and made of porcelain or other insulating material the same as that of the body 1. The outer face 100 of the flange 19, while generally convex in form, is provided with a centrally placed circular depression 20 concentric with a passage or hole 21 extending axially through said part 18 while at one side of this central hole, is a second and usually smaller passage extending parallel to it through the piece 18 to that end thereof distant from the flange 19 where it opens adjacent a shoulder 22 formed at a level slightly below that 110

of the end 23. This shoulder extends circumferentially around a greater or less portion of one side of this end and at a point distant from the side passage has opening 5 into it a channel 24 formed in one of the faces of the piece 18, in which it extends preferably, though not necessarily, parallel with the hole 21 to the under face of the flange 19. This, as indicated at 25, is preferably though not necessarily, radially recessed to form a continuation of said channel. A length of fuse wire 26 having a circularly curved portion at one end, extends through the side passage of the prismatic piece 18 in such manner that said curved portion lies within the recess 20 substantially concentric with the hole 21. The opposite end of said fuse wire then extends around the end of the capsule over the shoulder 22, and back toward the flange 19 through the channel 24, being finally bent radially outward in the recess 25 and terminating slightly inside of the outer edge of said flange. A metal disk 28, preferably 20 having a central threaded opening which is counter sunk on one face of said disk and surrounded by a conical collar 27 on the opposite face, is designed to rest on the circularly formed end of the fuse wire 26 25 in recess 20, and the screw 13 passes through this disk and the hole 21 into the central hole 12 of the bridge piece 11.

By setting up this screw, good electrical contact is assured between the terminal disk 30 or plate 28 and the end of the fuse wire 26, and it is noted that the same action, by drawing the prismatic block 18 into the fuse plug body 1, likewise causes the flange 19 to forcibly press the outwardly extending end 26^a of the fuse wire into electrical engagement with the inwardly turned flange 17 of the terminal shell 14, thereby establishing an electrical circuit from the terminal plate 28 through the fuse wire 26 to the threaded shell 14 so that the plug may be used in the well-known way as a safety device for electrical circuits.

In case of an overload in the circuit in which it is included, the "blowing" of the fuse wire would be visible through the mica plate and thereafter in order to replace said broken wire, the screw 13 is freed from the bridge piece 11 whereupon the fuse-carrying element or capsule may be removed from the body 1. By withdrawing the screw 13 and thus removing the disk 28 from the recess 20, it is possible to easily withdraw any part of the fuse wire still remaining in said recess or in the passage leading thereto. 50 60 A new length of fuse wire may now be placed in the recess, run through the side passage of the element 18, across the shoulder 22, down the outside channel 24 and outwardly across the face of the flange 19;— 65 it being noted that the thickness of the fuse

wire is greater than the depth of the recess 25 in said flange so that good electrical contact of said end with the flange 17 of the threaded shell 14 is assured.

By threading the screw 13 into the disk 70 28, these parts are held together against accidental separation and possible loss, and by providing the collar 27 on said disk there is obtained an increased contact surface in engagement with the fuse wire 26. In this case said disk or plate 28 is slightly less in diameter than the recess 20 of the fuse capsule 18 so that the under side of said disk is certainly drawn into engagement with the end of the fuse wire when the 80 screw 13 is set up.

One important advantage of the above described construction resides in locking the shell 14 to the body 10 by means of the capsule or fuse-carrying element of other than 85 circular section, and as a result, when the plug as a whole is screwed into or out of a socket or receptacle, the tendency of said shell to stick or resist movement is effectually overcome, since the rotative force applied by the operator to the part 9 and hence to the body structure 10, is transferred from the latter to the hexagonal or other non-circular capsule structure and thence to the inwardly extending flange 17 95 of the shell, which is consequently forced to turn without possibility of independent movement.

I claim:—

1. The combination in a fuse plug of a 100 body; a fuse-carrying element removably but non-rotatably mounted in said body with its fuse inclosed thereby; terminals respectively on the body and on said element normally connected through the fuse; 105 and a member extending through the fuse-carrying element, mechanically and separably connecting it to the body.

2. The combination in a fuse plug of a 110 body; a fuse-carrying element removably fitting into said body; a screw separably connecting the body and said element; a central terminal on the fuse-carrying element engaged by said screw; the fuse of said element extending over a portion of 115 the outside surface thereof and being electrically connected to said terminal; and a fuse body having a terminal shell including a portion clamped against the fuse by the action of said screw.

3. The combination in a fuse plug of a 120 body having an opening therethrough; a bridge piece spanning said opening; a fuse-carrying element removably fitting the opening of said body; a member extending 125 through said element into holding engagement with the bridge piece; with terminals respectively on said element and the body electrically connected through the fuse of the element.

4. The combination in a fuse plug of a body having an opening therethrough; a bridge piece spanning said opening; a fuse-carrying element removably fitting the opening of said body; a screw extending through said element into holding engagement with the bridge piece; with terminals respectively on said element and the body electrically connected through the fuse of the element.

5. The combination in a fuse plug of a body having an opening therethrough; a bridge piece spanning said opening; a fuse-carrying element removably and non-rotatably fitting the opening of said body; a member extending through said element into holding engagement with the bridge piece; with terminals respectively on said element and the body electrically connected through the fuse of the element.

6. The combination in a fuse plug of a body having an opening therein; a bridge piece spanning said opening; a block removably fitting the opening of the body; a screw passing through said block and threaded into the bridge piece; a terminal plate held to the block by the screw; a fuse having one end gripped by the said plate to the block and extending through the latter to the outside surface thereof; with a terminal shell on the body and including a portion clamped against the outer part of said fuse by the action of the screw.

7. The combination in a fuse plug of a body having an opening therethrough; a bridge piece spanning said opening adjacent one end thereof; a block of generally prismatic form non-rotatably fitting the opening of the body; a screw extending axially through said block into engagement with the bridge piece; a fuse extending through the block, over one end thereof and thence through an open recess toward the opposite end of the block; a terminal shell on the body having an inwardly extending portion placed to be engaged by an end portion of the fuse when said screw is set up; and a substantially central terminal plate on the block in electrical connection with the second end of the fuse.

8. The combination in a fuse plug of a body having an opening therein; a threaded terminal shell on the body having an inverted flange projecting at one end thereof; a flanged element removably fitting the

opening of the body; a fuse having one end extended outwardly over the flange of said element in position to engage the flange of the terminal shell; a center terminal on the flanged element connected to the fuse; and a member passing through said terminal mechanically and separably connecting the body and said element.

9. As a new article of manufacture a block of insulating material of other than circular cross section, having two parallel passages extending longitudinally through it and also having a groove in its side parallel with said passages; a terminal plate at one end of said block; with a fuse electrically connected to said plate, extending through one of the passages of the block thence back through the groove thereof and then projecting outwardly.

10. As a new article of manufacture a fuse-carrying element consisting of a block of insulating material having a longitudinally extending passage through its body and a groove in its outside surface substantially parallel to said passage, there being a recess at one end of the block connecting the adjacent ends of the passage and groove; a terminal plate at one end of the block; with a fuse electrically connected to said plate, extending therefrom through the passage, thence in the end recess circumferentially of the plug and back through the groove toward the plate-carrying end of the block.

11. As a new article of manufacture a fuse-carrying element consisting of a block of insulating material having a central recess and two longitudinally extending passages of which one opens into said recess, there being a groove formed in the outside surface of the block and a recess in the second end of the latter connecting said groove with the non-central passage; a terminal plate mounted in the central recess of the block; with a fuse wire having one end in said latter recess in electrical connection with the plate and extending through the non-central passage of the block, thence through the second-end recess of the block substantially concentric with the central passage and then back toward the opposite end of the block through the groove thereof.

In witness whereof I affix my signature.

HENRY T. PAISTE.
